UNITED STATES PATENT OFFICE

91,508

DESIGN FOR AN ELEVATED STORAGE TANK

Bryan M. Blackburn, Newnan, Ga., assignor to R. D. Cole Manufacturing Co., Newnan, Ga., a corporation of Georgia

Application September 26, 1933. Serial No. 49,350

Term of patent 14 years

To all whom it may concern:

Be it known that I, BRYAN M. BLACKBURN, a citizen of the United States, residing at Newnan, in the county of Coweta and State of Georgia, have invented a new, original, and ornamental Design for an Elevated Storage Tank, as shown in the accompanying drawing and described in the following specification, in which the sole figure is a perspective view of an elevated storage tank, embodying the design.

The tank is of round horizontal cross section.

I claim:

The ornamental design for an elevated storage tank as shown and described.

BRYAN M. BLACKBURN.
